(57) **CLAIM**

The ornamental design for action triggers embedded in mid-frame of a handheld device, as shown and described.

DESCRIPTION

FIG. 1 is a top plan view of action triggers embedded in mid-frame of a handheld device;

FIG. 2 is a right side elevation view of the action triggers embedded in mid-frame of a handheld device, a left side elevation view being the same as shown;

FIG. 3 is a top left perspective view of the action triggers embedded in mid-frame of a handheld device; and,

FIG. 4 is another top left perspective view of the action triggers embedded in mid-frame of a handheld device.

The broken lines, which define the bounds of the claimed design, form no part thereof. The broken lines showing a handheld device are for illustrative purpose only and form no part of the claimed design.

1 Claim, 4 Drawing Sheets
